UNITED STATES PATENT OFFICE.

EMIL K. VIETOR, OF RICHMOND, VIRGINIA.

PROCESS AND APPARATUS FOR DRYING TOBACCO LEAVES, ETC.

Application filed April 18, 1922. Serial No. 554,391.

To all whom it may concern:

Be it known that I, EMIL K. VIETOR, citizen of Germany, residing at Richmond, in the county of Chesterfield and 5 State of Virginia, have invented certain new and useful Improvements in Processes and Apparatus for Drying Tobacco Leaves, Etc.; and I do hereby declare the following to be a full, clear, and exact description of the invention, such as will enable others skilled in the art to which it appertains to make and use the same.

My invention consists in certain new and useful improvements in the process and apparatus for drying leaf tobacco strips in keeping condition, preparatory to packing the same in hogsheads for shipment, or to working up into commercial form.

My improved process and apparatus are 20 equally as well adapted to the drying of fruits, vegetables and other edibles, my principal object being to preserve the natural flavors, aroma and properties of the material treated which are lost if the material is 25 subject to an unnatural heat.

In describing my process, I shall, for illustrative purposes, set it forth as applied to tobacco, but it will be understood that I claim its use for drying not only tobacco, 30 but other vegetable and edible matter.

In drying tobacco and similar products, at the present time, two methods are employed, one to air dry them, that is to rack the products in a room to which the air has 35 access, and to allow such products to remain there until dry. This method, however, is very uncertain as regards the period of time necessary for thorough drying, which period may be from three to six months in duration according to the weather prevailing, as 40 the amount of moisture in the air constitutes an important factor, in this old method of drying.

Another method of drying the products 45 in question, consists in passing the same through a drying machine, or room where heat is maintained at from 150° to 250° F., but this method is very unsatisfactory, as such high degree of heat deprives the products treated, of their natural flavor and so-called vitamins.

My improved process obviates the above difficulties, in that I am able to accomplish the drying of tobacco and analogous products 55 in about ten hours, and at the same

time preserve all their natural flavors and properties.

In order that my process may be clearly understood, I have illustrated in the accompanying drawings a means by which it may 60 be practiced, and to which reference will be made as the description proceeds, and I have more particularly pointed out my invention in the appended claims.

In the drawings:—

Fig. 1 is a longitudinal sectional view of a drying room and apparatus, suitable for the working of my process.

Fig. 2 is a transverse sectional view of a portion of the same.

Fig. 3 is a plan view of the roof of the air space above the drying room, showing the air exits.

Fig. 4 is a similar view of the ceiling of the drying room, showing air outlets, which 75 may be of any desired shape.

Fig. 5 is a plan view of the floor of the drying room, showing apertures for admission of air to the drying room.

Fig. 6 is a plan view of the plenum chamber.

Similar numerals indicate identical parts throughout.

1 represents the interior of the drying chamber, the floor 2 of which is provided 85 with tracks 3 upon which run the trucks 4, carrying the tobacco or other product to be dried, and which are provided with the usual racks, etc., common to this sort of device.

The floor 2 is also provided with a number of perforations 5 which are preferably located between the tracks for the trucks, and are in staggered relation to each other, transversely of the floor. Hinged at 6, to 95 suitable supports or otherwise movably secured thereto, are doors 8 for the ingress and egress of the trucks.

Beneath the floor 2 is a plenum chamber 9 which is rectangular in shape and may be 100 provided with heating coils, for heating the air in said chamber.

In the form shown in the drawings, Figs. 1 and 6 I may provide the plenum chamber with a supplemental floor 10, which is inclined from the ceiling of the chamber at each end and side thereof down to a central point in the floor, as at 11, at which point there is an opening to receive a discharge duct 12 from the blower chamber 13.

The blower chamber is provided with heating coils 14 and an air intake 15. A fan 16 of any desired construction, is mounted in the chamber and is provided with suitable 5 driving means, as shown.

To provide for moistening the air in the plenum chamber, I provide pipes 17 having a plurality of moisture spraying nozzles 18, one of said nozzles being located near the 10 central portion of the chamber and adapted to emit a spray against a baffle 19 which drives the spray in opposite directions, as shown. 20 represents an intake pipe for the moisture, which may be steam if desired, 15 and supplies the same to the pipes 17.

21 represents apertures in the ceiling of the drying room, for the exit of the air, after it has absorbed the moisture from the tobacco or other vegetable matter in course 20 of drying and which are fewer in number than the intake apertures in the floor of the 25 drying room.

22 are apertures located in the roof of the building in which the drying room is located, for the final exit of the moisture laden air into the outside atmosphere, and which in turn are fewer in number than those of the ceiling of the drying room.

The apertures in the floor, ceiling and 30 roof are provided with dampers for controlling the ingress and egress of the air and a damper is also provided in the pipe leading from the blower chamber to the vent chamber.

35 In the blower chamber, the heating coil may be converted into a cooling coil, by passing a cooling fluid through the same, in a well known manner, so that cooled air may be fanned into the drying chamber, if desired.

40 From the above, it is believed the operation of my process will be apparent.

The door or doors 8 of the drying chamber are opened, and trucks provided with 45 racks upon which are hung or spread tobacco leaves or other matter to be dried, as shown at 26, are pushed into the chamber on the tracks 3.

It will be noted that I provide in my present form of structure for three trucks abreast, each truck running on three tracks, 50 as shown in Fig. 2.

It will also be noted that the air inlet apertures 5 are under each truck, and these 55 trucks act as baffles, causing the air to pass up through and around the contents of the truck, and come into intimate contact therewith, whereby the drying is expedited.

The air heated and moistened to the desired degree in the plenum chamber, passes 60 up through the inlet openings in the floor of the drying chamber, absorbs the moisture from the tobacco leaves or other vegetable matter being treated, as above set forth, and 65 passes out through the ceiling apertures 21,

in a single line over each row of trucks, as shown in Fig. 2, into the air space 23, above the ceiling and finally escapes into the atmosphere through the apertures or ventilators 22 in the roof.

70 It is obvious, that the apertures 22 in the roof being fewer in number than the number of apertures 21 in the ceiling and the latter fewer in number than the apertures 5 in the floor, the movement of the drying air 75 is retarded, and caused to contact most thoroughly with the contents of the trucks, undergoing the process.

It is also obvious that the process may be controlled in its operation, by the use of the 80 dampers in the apertures. For example, if the heat for drying or the moisture laden air for conditioning should not be distributed uniformly through the drying room, the apertures near the intake may be shut entirely, those toward the middle of the room may be opened only half way and those at the ends may be left entirely open. Uniformity of heat and moisture can thus be 85 readily obtained.

If cool air is required in the drying room, the air in the blower chamber may be cooled instead of heated, in any desired manner and the cooled air supplied to the plenum chamber and thence to the drying chamber. 90

95 It is obvious that by my arrangement of apparatus and use of the plenum chamber and registers or dampers in the floor and ceiling apertures, hot air may be evenly introduced and distributed into and through the drying chamber, by means of the fan or blower, and after the air has absorbed the moisture from the material being operated upon, it continues out into the atmosphere 100 through the apertures in the ceiling.

105 Thus, there is a continual change of air, and by my process and apparatus, vegetable and other matter may be dried at a natural temperature and below 100° F., whereby tobacco, fruit, vegetables or other edibles being dried retain all their fine natural flavor and aroma, which are now largely lost in the use of drying machines, the air in which is heated to from 150° to 250° F.

110 What I claim and desire to secure by Letters Patent is:—

1. A process for drying and conditioning tobacco leaves and analogous vegetable matter, which consists in placing said matter in a closed chamber and circulating dry air heated to a natural summer temperature of about 100° F. through said chamber, in individually regulated currents through and around said matter, whereby said matter is 115 thoroughly and quickly dried to a brittle condition, and then forcing moistened air in individually regulated currents up through the heating chamber and in and around said matter.

120 2. An apparatus for drying tobacco leaves 125

and analogous vegetable matter, which consists in a drying chamber, the floor and ceiling of which are provided with apertures, a plenum chamber beneath and an air space above said drying chamber, means for heating the air in the plenum chamber, and means for forcing said air through the apertures in the floor of the drying chamber, and out through the apertures in the ceiling 10 of the same.

3. An apparatus for drying tobacco leaves and analogous vegetable matter, which consists in a drying chamber, the floor and ceiling of which are provided with apertures, a plenum chamber beneath and an air space above said drying chamber, means for moistening the air in the plenum chamber, and means for forcing said moistened air into and through said drying chamber.

4. An apparatus for drying tobacco leaves and analogous vegetable matter, which consists in a drying chamber, the floor and ceiling of which are provided with apertures, the total area of the apertures of the 25 ceiling being less than the total area of the apertures of the floor, a plenum chamber beneath and an air space above said drying chamber, means for heating and moistening the air in the plenum chamber, means for forcing the air from the plenum chamber through the apertures in the floor and ceiling of the drying chamber, and means located in the said apertures for regulating the passage of air therethrough.

5. An apparatus for drying tobacco leaves 35 and analogous vegetable matter, which consists in a drying chamber, the floor and ceiling of which are provided with apertures, a plenum chamber beneath and an air space above said drying chamber, means for 40 heating and moistening the air in the plenum chamber and means for forcing the air from the plenum chamber through the apertures in the floor and ceiling of the drying chamber, the said plenum chamber being provided with a downwardly inclined floor, the inclined portions converging at a 45 central point.

6. An apparatus as claimed in claim 5 in which the plenum chamber is provided 50 with pipes having spray nozzles for spraying moisture into said chamber.

7. An apparatus for drying tobacco leaves and analogous vegetable matter, which consists in a drying chamber, the floor and ceiling of which are provided with apertures, a plenum chamber beneath and an air space above said drying chamber, means for moistening the air in the plenum chamber, a blower chamber, a pipe connecting the 55 blower chamber and plenum chamber, means located in the blower chamber for forcing air into the plenum chamber, and thence into the drying chamber, and means for changing the temperature of the air in the blower 60 chamber as desired.

In testimony whereof I affix my signature.
EMIL K. VIETOR.
